[57] CLAIM

The ornamental design for a loud-speaker device for cars, substantially as shown and described.

DESCRIPTION

FIG. 1 is a top plan view of a loud-speaker device for cars showing our new design;

FIG. 2 is a side elevational view thereof, the opposite side being identical to the one shown;

FIG. 3 is a bottom plan view thereof; and

FIG. 4 is a transverse sectional view taken on lines 4—4 of FIG. 2.

FIG.1.

FIG.2

FIG.3.

FIG.4.
